UNITED STATES PATENT OFFICE.

AUGUST MORTENSEN AND MARTIN L. HIGLEY, OF SAN FRANCISCO, CALIFORNIA.

DESIGN FOR A SONG-WHISTLE.

56,986.

Specification for Design.

Patented Jan. 25, 1921.

Application filed July 6, 1920. Serial No. 394,335. Term of patent 3½ years.

To all whom it may concern:

Be it known that we, AUGUST MORTENSEN and MARTIN L. HIGLEY, citizens of the United States, and residents of the city and county of San Francisco and State of California, have invented a new, original, and ornamental Design for a Song-Whistle, of which the following is a specification, reference being had to the accompanying drawing, forming a part thereof.

In the drawing:

Figure 1 is a side elevation.

Fig. 2 is a plan.

What we claim is:—

The new and ornamental design for a song whistle substantially as shown.

In testimony whereof we have hereunto set our hands this 24th day of June, 1920, in the presence of the two subscribed witnesses.

AUGUST MORTENSEN.
MARTIN L. HIGLEY.

Witnesses:

J. H. MORGAN,
JESSIE TOMPKINS.
